UNITED STATES PATENT OFFICE.

SYLVESTER JOSEPH POCOCK, OF ST. MARYS, ONTARIO, CANADA, ASSIGNOR OF ONE-HALF TO JOHN KNOX RICHARDSON, OF ST. MARYS, ONTARIO, CANADA.

DISPENSER FOR LUBRICATING OILS.

Application filed September 27, 1928. Serial No. 138,072.

My invention relates to improvements in dispensers for lubricating oils, and the object of the invention is to devise a single, cheap and easily operated dispenser for dispensing small quantities of liquid such as lubricating oil which may be purchased by a single coin, and in which simple means is provided for varying the amount purchased by such coin, or in other words varying the purchasing power of the coin inserted in the machine, and it consists essentially of the arrangement and construction of parts as hereinafter more particularly explained.

Fig. 1 is a view partially in section and partially in elevation of my device applied to an oil dispensing tank.

Fig. 2 is an enlarged sectional detail of the major portion of my mechanism. Fig. 3 is a plan view. Fig. 4 is a sectional detail.

In the drawings like characters of reference indicate corresponding parts in each figure.

1 indicates a tank connected in the usual manner to the main supply tank and provided with a piston 2 and piston rod 3 operating therein. 4 indicates the inlet pipe for feeding the oil into the tank 1 and 5 the outlet pipe, such pipes being suitably arranged and valved according to common practice. 6 is a rack formed integral with or suitably connected to the rod 3. 7 is a casing mounted upon suitable supports such as indicated at 8. The casing 7 is provided in its front wall with an orifice 9 provided with a hinged cover 10 which is firmly locked in position by a hasp and padlock such as indicated at 11.

12 is a shaft extending transversely through the casing and journalled at one end in the wall of the casing and at its opposite end in a suitable journal bracket 13 mounted to extend centrally of the opening 9. 14 is a slide bar provided with a rectangular orifice 15 through which the shaft 12 extends so as to permit the free horizontal longitudinal movement of the slide bar 14. 16 is a disc secured to the shaft 12 and provided around its outer periphery with angular teeth 17. 18 is a spiral groove formed in the face of the disc 16 and provided at suitable distances apart with small orifices 19 formed in the face of the groove and spaced apart and opposite each of which are quantity indications corresponding to the amount of liquid sold as will hereinafter appear.

20 is a pin which may be inserted in any one of the orifices 19. 21 is a coin receiving slot in the upper wall of the casing 7. 22 is a

lever pivotally mounted at its upper end between walls 23 depending from each side of the slot 21. 24 is a slide bar slidably held within a slideway 25 and provided at its outer end with a depending portion 26 provided with a pin 27 extending into the groove 18. The opposite end of the slide bar 24 is pivotally connected to the lower end of the lever 22 as indicated at 28.

29 is a pressure spring forcing the lever 22 inward for a purpose which will hereinafter appear.

30 is a detent pivoted at 31 between the walls 23, the upper portion above its pivot point extending into the path of the coin inserted through the slot 21 so that the distance between such upper end and the opposing portion of the lever 22 is less than the diameter of the inserted coin. The lower end of the detent 30 is provided with a tail piece 32. 33 is a lever mounted centrally of its length upon the wall of the casing 7 as indicated at 34. The upper end of the lever is pivotally connected with a tail piece 32 as indicated at 35 and at its lower end to the slide bar 14 as indicated at 36. 39 is a spring bearing against the lower portion of the lever 33 below its pivot 34. 40 and 41 are spring pressed latch dogs adapted to alternately engage with the teeth 17 of the disc 16. 42 is the operating crank arm secured to the shaft 12. 43 is a gear also secured to the shaft 12 and meshing with the teeth of the rack 6.

In order that the pin 27 follows the groove 18 as the disc 16 is rotated the depending portion 26 of the slide bar 24 is provided with a vertical slot in which is mounted a slide piece 44 upon which the pin 27 is mounted.

Having described the principal parts involved in my invention I will briefly describe the operation of the same.

The crank shaft 12 is rotated by the crank arm 42 in the direction of arrow, see Figure 2. By this means the disc 16 is rotated in a corresponding direction until the pin 27 reaches the opposite end of the groove 18, that is the outer end of the groove. Simultaneously with this operation the gear 43 in mesh with the teeth of the rack 6 carries the rack in a downward direction so that the oil contained within the tank 1 below the piston 2 is forced through the piston valve 2* above the piston. The pin 20 has been previously set in one of the small orifices 19 opposite the indicating amount of gasoline to be sold for the coin in-

serted by the purchaser in the slot 21. The setting of this pin 20 of course is performed by the vendor at the beginning of each day's sale, the hinged cover 10 being then closed and locked by the vendor.

5 The purchaser after rotating the crank arm 42 in the direction of arrow as above described inserts his coin in the coin slot 21 between the inner edge of the lever 22 and the 10 opposing inwardly projecting ends of the detent 30. The spring 29 is relatively a stronger spring than the spring 39 and therefore when a coin is inserted as above described the lever 22 is held from movement and the 15 detent 30 swung outward from the dotted line position to the full line position shown in the drawing. By this means the lever 33 is swung on its pivot 34 moving the slide bar 14 from the dotted line position to the full line position shown thereby carrying the spring latch 40 out of engagement with the teeth 17 and the 20 spring latch 41 into engagement with the teeth.

When this operation is performed the operator turns the crank arm 42 in the opposite direction to arrow, the engaged latch dog 41 permitting of this movement. By this operation the disc 16 is also turned in the reverse direction to arrow carrying the pin 20 into engagement with the pin 27 and thereby forcing the pin horizontally in the direction of arrow and carrying the slide bar 24 in a corresponding direction so as to carry the lever 22 out of engagement with the coin, that is in the dotted 30 position shown allowing the coin to drop and pass into the till. The engagement of the pin 20 with the pin 27 by limiting the rotation of the disc 16 also limits the distance to which the gear 43 is turned and the extent to which 35 the rack 6 is carried into the dispensing direction thereby limiting the upward movement of the piston 2 to discharge a quantity corresponding to that to which the pin 20 has been set for. When the quantity is to be 40 varied all the vendor has to do is to open the cover 10 and remove the pin 20 from its orifice and insert it in any one of the other orifices according to the quantity of oil desired to be sold.

50 From this description it will be seen that I have devised a very simple form of dispensing apparatus which will dispense any given quantity of oil which is to be sold for a coin inserted in the machine according to the 55 market value of the oil at any given day or in accordance with the purchasing power of the coin for that particular day.

What I claim as my invention is:—

1. In an oil dispenser, the combination with 60 the operating shaft of the dispenser, of a casing having a coin slot and into which the aforesaid shaft extends, a disc secured to the shaft within the casing, a stop adjustable circumferentially upon the disc, means movable longitudinally for locking the disc and shaft

from rotation in the dispensing direction and permitting the rotation in the reverse direction, means operated by the insertion of a coin in the coin slot for releasing such locking means to permit the disc and shaft to operate 70 in the dispensing direction and adapted to grip and hold the coin, and means actuated by the stop as the disc is rotated in the dispensing direction for releasing the coin.

2. In an oil dispenser, the combination with 75 the operating shaft of the dispenser, of a casing having a coin slot and into which the aforesaid shaft extends, a disc secured to the shaft within the casing, a stop adjustable circumferentially upon the disc, means movable longitudinally for locking the disc and shaft from rotation in the dispensing direction and permitting the rotation in the reverse direction, means operated by the insertion of a coin in the coin slot for releasing such locking 80 means to permit the disc and shaft to operate in the dispensing direction and simultaneously locking the disc and shaft from rotation in the reverse direction.

3. In an oil dispenser, the combination with 90 the operating shaft of the dispenser, of a casing having a coin slot and into which the shaft extends, a disc secured to the shaft within the casing, a stop adjustable circumferentially upon the disc, a slide bar mounted 95 in the casing to move longitudinally, means carried by the slide bar at each side of the disc to alternately engage with the disc as the slide bar is moved in alternate directions to alternately lock the disc and shaft from 100 rotation in the dispensing direction and in the reverse direction, means operated by the insertion of a coin in the coin slot for moving the slide bar to release the disc to operate in the dispensing direction and adapted 105 to grip and hold the coin, and means actuated by said stop as the disc is rotated in the dispensing direction for releasing the coin from such holding means.

4. In an oil dispenser, the combination with 110 the operating shaft of the dispenser, of a casing having a coin slot into which the shaft extends, a disc secured to the shaft within the casing and free normally to revolve in a direction reverse to the dispensing direction, 115 a stop adjustable circumferentially upon the disc, a slide bar mounted in the casing to move longitudinally, a spring pressed latch member carried by the slide bar at each side of the disc, a toothed gear carried by the disc 120 with which the spring pressed latch member alternately engages, means operated by the insertion of a coin in the coin slot for moving the slide bar to release the disc to operate in the dispensing direction and to 125 simultaneously lock the disc from rotation in the reverse direction and adapted to grip and hold the coin, and means actuated by said stop as the disc is rotated in the dispensing direction for releasing the coin.

5. In an oil dispenser, the combination with the operating shaft of the dispenser, of a casing having a coin slot and into which the shaft extends, a disc secured to the shaft within the casing and having a spiral groove in a face thereof, a stop, means for adjustably holding the stop in spaced apart positions within the aforesaid groove, means movable longitudinally for locking the disc and shaft from rotation in the dispensing direction and permitting rotation in the reverse direction, means operated by the insertion of a coin in the coin slot for releasing such locking means to permit the disc and shaft to operate in the dispensing direction and adapted to grip and hold the coin, and means operated by said stop as the disc is rotated in the dispensing direction for releasing the coin from the coin holding means.
- 10 6. In an oil dispenser, the combination with the operating shaft of the dispenser, of a casing having a coin slot and into which the shaft extends, a disc secured to the shaft within the casing and having a spiral groove in a face thereof, a stop, means for adjustably securing the stop in spaced apart positions within the groove, a stop support, a coacting stop carried by the support and projecting into the groove and adapted to travel radially inward or outward as the disc is revolved, means carrying a sliding latch for locking the disc and shaft from rotation in the dispensing direction and permitting the rotation in the reverse direction, means operated by the insertion of a coin in the coin slot for releasing such locking means to permit the disc and shaft to operate in the dispensing direction and adapted to grip and hold the coin, and means actuated by the stop engaging the coacting stop for releasing the coin as the disc is rotated in the dispensing direction.
- 15 7. In an oil dispenser, the combination with the operating shaft of the dispenser, of a casing having a coin slot and into which the shaft extends, a disc secured to the shaft within the casing, a stop adjustable circumferentially upon the disc, means movable longitudinally for engaging the disc alternately from opposite directions for locking the disc and shaft from rotation in one direction and permitting rotation in the reverse direction, a detent pivotally mounted at one end of the coin slot, a spring pressed member pivotally mounted at the opposite end of the coin slot and between which and the pivoted detent the coin inserted through the slot is adapted to be forced to swing the detent outward, means operated by the swinging of the detent for releasing the locking means to permit the disc to rotate in the dispensing direction, and means coacting with the adjustable stop carried by the disc for moving the spring pressed member away from the coin to release it as the disc is rotated in the dispensing direction.
- 20 8. In an oil dispenser, the combination with the operating shaft of the dispenser, of a casing having a coin slot and into which the shaft extends, a disc secured to the shaft within the casing, a stop adjustable circumferentially of the disc, a slide bar mounted in the casing to move longitudinally, means carried by the slide bar for alternately engaging the disc to lock it from rotation, a detent pivotally mounted at one end of the coin slot, a spring 75 pressed member pivotally mounted at the opposite end of the coin slot and between which and the detent the inserted coin is pressed, a tail piece depending from the detent, a lever mounted centrally of its length and pivotally 80 connected at one end to the tail piece of the detent and at the opposite end to the slide bar, and means coacting with the adjustable stop for moving the spring pressed member out of engagement with the coin as the disc is rotated in the dispensing direction.
- 25 9. In an oil dispenser, the combination with the operating shaft of the dispenser, of a casing having a coin slot and into which the shaft extends, a disc secured to the shaft within the 90 casing, a stop adjustable circumferentially upon the disc, means for locking the disc and shaft from rotation in the dispensing direction and permitting the rotation on the reverse direction, means operated by the insertion of a coin in the coin slot for releasing such locking means to permit the disc and shaft to operate in the dispensing direction and comprising a pair of opposing gripping members, a movable slide bar connected to one of said 100 gripping members, and means coacting with the adjustable stop for moving said gripping member out of its gripping position to release the coin as the disc is turned in the dispensing direction.
- 30 10. In an oil dispenser, the combination with the operating shaft of the dispenser, of a casing having a coin slot, a disc secured to the shaft within the casing, a stop adjustable circumferentially upon the disc, means including a bar mounted to slide longitudinally for locking the disc and shaft from rotation in the dispensing direction and permitting the rotation in the reverse direction, means operated by the insertion of a coin in the coin 110 slot for releasing such locking means to permit the disc and shaft to operate in the dispensing direction and adapted to grip and hold the coin, and means operated by said stop for releasing the coin during the dispensing operation.
- 35 11. In an oil dispenser, the combination with the operating shaft of the dispenser, of a casing having a coin slot and into which the shaft extends, a disc secured to the shaft within the casing, a stop adjustable circumferentially upon the disc, means including a bar mounted to slide longitudinally for locking the disc and shaft from rotation in the dispensing direction and permitting rotation in 120 the reverse direction.
- 40 12. In an oil dispenser, the combination with the operating shaft of the dispenser, of a casing having a coin slot and into which the shaft extends, a disc secured to the shaft within the casing, a stop adjustable circumferentially upon the disc, means including a bar mounted to slide longitudinally for locking the disc and shaft from rotation in the dispensing direction and permitting rotation in 130 the reverse direction.

the reverse direction, a detent pivotally mounted at one end of the coin slot, a spring pressed member pivotally mounted at the opposite end of the coin slot and between which and the pivoted detent the coin inserted through the slot is adapted to be forced to swing the detent outward, means operated by

the swinging of the detent for releasing the locking means to permit the disc to rotate in the dispensing direction, and means operated by said stop for moving the spring pressed member away from the coin to release it as the disc is rotated in the dispensing direction.

SYLVESTER JOSEPH POCOCK.
